BALING PRESS.

APPLICATION FILED DEC. 23, 1905.

2 SHEETS—SHEET 2.

THE NORRIS PETERS CO., WASHINGTON, D. C.

UNITED STATES PATENT OFFICE.

JOHN J. STOPPLE, OF DALLAS, TEXAS.

BALING-PRESS.

No. 844,053.

Specification of Letters Patent.

Patented Feb. 12, 1907.

Application filed December 23, 1905. Serial No. 293,107.

To all whom it may concern:

Be it known that I, JOHN J. STOPPLE, a citizen of the United States, residing at Dallas, in the county of Dallas and State of Texas, have invented certain new and useful Improvements in Baling-Presses; and I do hereby declare the following to be a full, clear, and exact description of the invention, such as will enable others skilled in the art to 10 which it appertains to make and use the same.

This invention relates to improvements in baling-presses.

The object of the invention is the provision 15 of means for facilitating the compression of material for forming a bale.

With this and other objects in view the invention consists of certain other novel constructions, combinations, and arrangements 20 of parts, as will be hereinafter fully described, illustrated in the accompanying drawings, and more particularly pointed out in the claims hereto appended.

In the drawings, Figure 1 is a perspective 25 view of a mechanism constructed in accordance with the present invention. Fig. 2 is a longitudinal vertical sectional view of the mechanism depicted in Fig. 1. Fig. 3 is a fragmentary horizontal sectional view of the 30 framework of the press, showing the pivoted retainers or dogs in position thereon. Fig. 4 is a view of the guiding means for the draftable, partly shown in front elevation and transverse section. Fig. 5 is a perspective 35 view of the bracket which supports the guide pulley or sheave. Fig. 6 is a transverse sectional view of the framework, showing the bracing means for the links upon which the lever is fulcrumed.

40 Referring to the drawings by numerals, 1 designates the parallel sled-runners, upon which is mounted a framework 2. The framework 2 is of any preferred structure and is provided with a compression-chamber, within which is positioned a plunger 3. A plate 4 is pivotally secured at its lower end to the plunger 3 for closing the bottom of the hopper 5 when the plunger is at the limit of its compression-stroke.

45 A lever 6 is pivoted near its lower end, as at 7, to the plunger 3 and is fulcrumed, as at 8, upon the upper ends of links 9 9, which links are preferably pivotally mounted upon a transverse rod or shaft 10, carried upon the 50 sides of the framework 2. The rod 10 is preferably journaled in annular members or col-

lars 10'. These collars 10' are carried by the sides of the framework 2. It has been found desirable to brace the links 9 9. This is accomplished by preferably employing crossed braces 9' 9', each one of which is secured at its upper end to one of the links and at its lower end to the opposite link. The braces 9' prevent any wabbling or lateral movement of the lever.

55 A yoke 11 is pivotally mounted, as at 12, upon the sides of the framework 2. The yoke is preferably an inverted substantially U-shaped structure. I preferably employ a pair of springs 12 for connecting the upper 70 portion of the yoke 11 to the links 9. Each spring 12 is connected at its upper or outer end to the yoke 11 and at its opposite end to one of the links 9, near the lever 6. The yoke 11 may be adjusted forward (see arrow, 75 Fig. 1) for tensioning the springs 12 by positioning transverse fastening means—as, for instance, bolts 13—in the apertures 14 of the brace bars or rods 15, which are pivotally connected to the sides of the yoke 11, as at 80 16. It will therefore be obvious that the adjustable braces 15 constitute adjusting means for the yoke 11 and tensioning means for the springs 12.

85 A horizontal shaft 17 is journaled in bearings 18. The bearings 18 are carried by the sides of the framework 2. A wheel 19, which is fixed to the shaft 17, is provided with a peripheral groove. Power-conveying means—as, for instance, cable 20—is secured, as at 90 21, in the groove of the wheel 19.

An eccentric-disk 22 is fixed to the shaft 17. This eccentric-disk 22 is provided with a tangential arm 23 and a cut-out portion 24. The outer end of arm 23 and the lever 6 are 95 connected by suitable flexible means—as, for instance, chain 25. By employing a hook 26, carried by lever 6, any slack in the chain may be taken up. The portion of the arm 23 and eccentric-disk 22 which is engaged by 100 the chain 25 is grooved, as at 27, so that the said chain or connecting means 25 may be seated within said groove 27 as the lever 6 is moved downwardly for actuating the plunger 3. Upon referring to Fig. 2 it will be 105 noted that the chain or connecting means 25 is positioned within the groove 27, and thereby preventing said connecting means from being removed off of said arm and eccentric. It has been found from practical experience 110 that a material advantage is obtained by employing the arm 23 and securing the connect-

ing means at its outer end, as upon rotating the eccentric-disk the lever 6 will be caused to rapidly descend at first, and as the resistance upon the plunger 3 increases, owing to the charge becoming more compressed, the leverage derived from the eccentric-disk 22 will increase as the lever 6 approaches its lowest position. It will therefore be seen that the lever 6 constitutes one lever means, while the eccentric-disk constitutes an auxiliary lever means, thereby producing progressive double-lever means for actuating the plunger 3 upon its compression-stroke.

It has been found that the chain or other suitable connecting means 25 will stretch to a certain degree, and it often occurs that the operator fails to take up this slack, which if the eccentric-disk is not cut away, as at 24, will wreck the machine, because the upper end of the lever 6 will be forced against the periphery of the eccentric-disk in its downward movement, necessitated for the completion of the compression-stroke of the plunger 3. In my improved structure of the eccentric-disk 22 this liability of breaking or wrecking the machine is obviated, even if the slack of the chain is not taken up, as the cut-away portion 24 will not permit the upper end of the lever 6 to come in contact with the eccentric-disk, but will permit the arm 23 to bear down upon the upper edge of the lever, thereby stopping the draft-animal which may be attached to the cable 20, for the lever 6 and the eccentric 22 are locked against further movement.

Guiding means is employed for facilitating the positioning of the draft-cable in the peripheral groove of wheel 19. This guiding means comprises a bracket which is provided with a horizontal apertured base-plate 28, having a vertical flange 29 at one of its longitudinal edges. Parallel arms 30 are integral with the flange 29 and plate 28. Each one of these arms is formed with an aperture 31 near its outer end, within which shaft 32 is positioned. These arms are curved for placing the shaft above the plate 28, thereby positioning the guide-pulley 33 above the said plate 28. The guide pulley or sheave 33 is provided with a bore or transverse aperture 34 of sufficient diameter to permit said guide-pulley to freely revolve upon the shaft 32, as will be clearly seen in Fig. 4. The shaft 32 is of sufficient length to permit the guide-pulley to have a slight longitudinal movement thereon, if necessary, for co-operating with the wheel 19, whose grooved periphery is positioned within the grooved periphery of the guide-pulley 33. It will therefore be obvious that the guide-pulley 33, owing to its overlapping a portion of the periphery or rim of wheel 19, constitutes revolute guiding means for the cable 20, said guiding means being capable of lateral movement, which is necessary if the bearings 18

of shaft 17 should become worn. The bracket for supporting the guide-pulley 33 is preferably secured to a transverse beam 35. The plate 28 is secured against the bottom surface of the beam 35, while the flange 29 engages the outer longitudinal edge of the same. (See Fig. 5.)

A staking device for securing the press in a fixed position during the operation of the same is employed. Said device comprises a pair of downwardly-extending parallel brake-pins 36, which are pivotally connected, as at 37, Fig. 2, to the front end of the parallel sled-runners 1. The brake-pins are of sufficient length to engage the transverse beam 35 when said pins are sunk into the ground, the beam 35 limiting the pivotal downward movement of said pins. If the pivotal downward movement of these brake-pins was not limited, said pins would turn upon their pivots 37, permitting the press to pass or ride over the same, and subsequently said pins would be drawn out of the ground with their points extending to the rear of the machine. The parallel pins are connected by a horizontal rod 38. A clevis 39 is secured to the beam 35, and attached to said clevis is preferably a chain 40, to which is attached a draft-animal for hauling the press. It will be obvious upon drawing chain 40 taut that the pins 36 will be lifted out of or from engagement with the ground, owing to the engagement of the rod 38 with said chain 40.

Referring particularly to Fig. 3, I form elongated slots or openings 41 in the framework 2, and within each of these slots and pivotally mounted, as at 42, upon the framework is a retainer or dog 43. Each retainer comprises a substantially straight body provided with a curved portion 44, terminating in a straight rear extension 45, the extension 45 constituting a finger or arm, which extends substantially parallel with the body. Upon each body there is formed a tapering nose 46, projecting into the compression-chamber. Upon the body, opposite to the nose 46, is formed a head 47, which constitutes a stop that engages one side of the framework, thereby limiting the inward movement of the nose 46. For holding the nose 46 in the compression-chamber I employ suitable means for exerting an outward pressure upon the rear extension 45—as, for instance, a flat spring 48, which is curved so as to engage the inner face of the extension 45. The spring is secured at one end to the side of the framework, and its outer free end presses against the extension 45. It will be noticed that the noses 46 may be forced outward by passing a division-plate 125 toward the rear of the compression-chamber; but as soon as the division-plate passes the retainers or dogs the springs 48 will force the noses 46 into the compression-chamber, while the head 47 will limit the inward movement of the nose 46.

movement of said noses. The plunger 3 is free to reciprocate within the compression-chamber past the retainers or dogs 43, for the reason that slots or grooves are formed upon 5 the sides of the plunger registering with the similar openings 41 of the framework 2. The material being operated upon may be pressed past the said retainers or dogs by contact with the beveled surface 49, the retainers or dogs swinging upon their pivots 42 to permit such passage, but being thrown back to their normal position after such passage, preferably by means of the springs 48.

By employing the retracting-springs 12 and the arm 23 of eccentric-disk 22 the draft-cable 20 is wound around the wheel 19 fast enough to take up any slack that occurs in said cable 20 during the backing of the draft-animal preparatory for advancing to complete another stroke of the plunger 3. By the peculiar structure of the mechanism said advantage is obtained, for it will be readily understood that if the mechanism worked slowly the swingletree and the slack in cable 20 would hit against the rear legs of the draft-animal and be likely to be broken by said animal stepping upon the same. From practical experience this undesirable result and the slow operation of the press is obviated, as the cable 20 is practically taut at all times, for my mechanism works rapidly whether the lever 6 and links 9, constituting a toggle, and the eccentrics 22 are being operated or whether said members are moving 35 from the position similar to that depicted in Fig. 2 to their normal position illustrated in Fig. 1.

Owing to the employment of the arm 23 upon the eccentric, the lever 6 is moved down 40 very rapidly at the start to take up the slack, and it throws a greater strain on the animal at the start than at the finish, thus equalizing the pull from start to finish.

What I claim is—

- 45 1. In a baling-press, the combination with a framework, a compression-chamber formed in said framework, a plunger therefor and means for operating said plunger, of a brake comprising a plurality of pins pivotally secured to said framework, and means for limiting the downward movement of said pins.
- 50 2. In a baling-press, the combination with a framework provided with a compression-chamber, a plunger operating in said compression-chamber, a lever engaging said plunger, an eccentric-disk, provided with a cut-away portion, mounted upon said framework, said cut-away portion of the disk being formed for permitting the lever to pass said disk 55 without engaging the same upon the compression-stroke of the plunger, means for connecting said eccentric-disk and lever, and means for rotating said eccentric-disk and thereby imparting movement to said lever and plunger.

3. In a baling-press, the combination with a framework provided with a compression-chamber, a plunger operating in said compression-chamber, a lever engaging said plunger, of an eccentric-disk provided with 70 a tangential arm and with a cut-out portion, carried by said framework, flexible connecting means secured to said arm and lever, and means for imparting rotary movement to said disk for actuating said lever and plunger. 75

4. In a baling-press, the combination with a framework, provided with a compression-chamber, a plunger operating in said compression-chamber, of links pivotally mounted at their lower ends upon said framework, 80 a lever pivotally connected at its lower end to said plunger and fulcrumed upon the upper ends of said links, a shaft carried by said framework, an eccentric-disk, provided with a tangential arm and with a cut-out portion, 85 fixed to said shaft, said disk and arm provided with a groove, flexible connecting means secured to said arm and lever, means for exerting an upward pull upon said links, and means for imparting rotary movement 90 to said shaft and disk and thereby actuating said lever and plunger, said lever, links and eccentric-disk constituting progressive, double-lever means.

5. In a baling-press, the combination with 95 a framework provided with a compression-chamber, a plunger operating in said compression-chamber, of a pair of links pivotally mounted upon said framework, a lever fulcrumed upon said links and engaging said 100 plunger, flexible means for moving said lever for operating said plunger, an eccentric-disk for operating said flexible means, a pulley for rotating said disk, means secured to said pulley for rotating the same, and means for guiding the means for rotating the said pulley. 105

6. In a baling-press, the combination with a framework provided with a compression-chamber, a plunger operating in said compression-chamber, of links carried by said framework, a lever fulcrumed upon said links and engaging said plunger, a yoke pivotally mounted upon said framework, springs connecting said yoke and links, each spring connected at one end to said yoke and at its opposite end to a link, means for adjusting said yoke for controlling the tension of said springs, and means for moving said lever upon its fulcrum for actuating said plunger. 110 115

7. In a baling-press, the combination with 120 a framework, provided with a compression-chamber, a plunger operating in said compression-chamber, of a link pivoted upon said framework, a lever fulcrumed upon said link and engaging said plunger, a yoke movably 125 mounted upon said framework, a spring connected at one end to said yoke and at its opposite end to said link, a brace connected at one end to said yoke and adjustably secured at its opposite end to said framework, and 130

means for moving said lever upon said fulcrum for actuating said plunger.

8. In a baling-press, the combination with a framework, provided with a compression-chamber, a plunger operating in said compression-chamber, of a link pivotally mounted upon said framework, a lever fulcrumed upon said link and engaging said plunger, a substantially U-shaped, inverted yoke pivoted upon said framework, and adjustable bracing means carried by said framework and yoke and being capable of securing said yoke in an adjustable position for tensioning said spring, and means for moving said lever upon its fulcrum for actuating said plunger.

9. In a baling-press, the combination with a framework, provided with a compression-chamber, a plunger operating in said compression-chamber, of lever means for actuating said plunger, a yoke pivotally mounted upon said framework, elastic means for connecting said yoke and lever means, and adjustable bracing means secured to said lever and framework and being capable of controlling the tension of said elastic means.

10. In a baling-press, the combination with a framework provided with a compression-chamber, a plunger operating in said compression-chamber, a pair of links pivotally mounted upon said framework, a lever fulcrumed upon the upper ends of said links and connected to said plunger at its lower end, a substantially U-shaped, inverted yoke pivotally mounted upon said framework, springs connecting said yoke and links, a brace adjustably secured to each side of said yoke and framework, and means for moving said lever upon its fulcrum for actuating said plunger.

11. In a baling-press, the combination with a framework provided with a compression-chamber, a plunger operating in said compression-chamber, lever means for actuating said plunger, of a yoke pivotally mounted upon said framework, a spring connecting said yoke and lever means, a pair of braces carried by said yoke and framework, each brace comprising a straight body provided at one end with an aperture, and at its opposite end with a plurality of apertures, and means engaging the apertured ends of said brace, yoke, and framework for securing said yoke in an adjusted position, whereby said yoke and braces are capable of controlling the tension of said spring.

12. In a baling-press, the combination with a framework provided with a compression-chamber, a plunger operating in said compression-chamber, a shaft carried by said frame, lever means carried by said framework and coöperating with said plunger, means connecting said shaft and lever means, of a wheel provided with a groove, carried by said shaft, a pulley provided with a peripheral groove, carried by said framework, the

grooved portion of said pulley overlapping part of the grooved portion of said wheel, power-conveying means secured within the groove of said wheel and adapted to pass between the overlapped portion of said wheel and the overlapping portion of said pulley, said overlapped and overlapping portions of said wheel and pulley, respectively, constituting guiding means.

13. In a baling-press, the combination with a framework provided with a compression-chamber, a plunger operating in said compression-chamber, lever means for actuating said plunger, of a wheel provided with a peripheral groove, carried by said framework, revoluble guiding means carried by said framework and secured contiguous to said wheel, and means connecting said wheel and lever means.

14. In a baling-press, the combination with a framework provided with a compression-chamber, a plunger operating in said compression-chamber, lever means carried by said framework and coöperating with said plunger, of a wheel carried by said framework, said wheel provided with a peripheral groove, means connecting said wheel to said lever means, a bracket carried by said framework, said bracket comprising a plate provided with a flange upon one edge, parallel arms integral with said flange and plate, a shaft carried by said arms, a grooved pulley carried by said shaft, said pulley overlapping a portion of said wheel, and power-conveying means secured within the peripheral groove of said wheel and pulley.

15. In a baling-press, the combination with a framework, provided with a compression-chamber, a plunger operating in said compression-chamber, of a wheel carried by said framework, said wheel provided with a peripheral groove, means connecting said wheel to said lever means, a bracket carried by said framework, said bracket provided with a shaft, a pulley loosely mounted and capable of longitudinal movement upon said shaft, the pulley overlapping a portion of said wheel, and power-conveying means positioned within the overlapped portion of said wheel and the overlapping portion of said pulley.

16. In a baling-press, the combination with a framework provided with a compression-chamber, a plunger operating in said compression-chamber, lever means for actuating said plunger, of a grooved wheel carried by said framework, means for connecting said wheel and lever means, and laterally movable and revoluble guiding means positioned contiguous to and coöperating with said wheel.

17. In a baling-press, the combination with a framework provided with a compression-chamber and a plunger operating therein, the side walls of said compression-cham- 130

ber being formed with longitudinal slots, of a retainer pivotally mounted within each of said slots, said retainer comprising a body provided at its rear end with a curved portion terminating in a rearward extension, the extension parallel with said body, a head and a nose formed upon the forward end of said body, and means for exerting an outward pressure upon the rearward extension for normally holding the nose within said compression-chamber.

18. In a baling-press, the combination with a framework provided with a compression-chamber and a plunger operating therein, the side walls of said compression-chamber being formed with longitudinal slots, of a retainer pivotally mounted within each of said slots, said retainer comprising a body provided with a head positioned at substantially right angles to said body, said head constituting a stop for limiting the inward, pivotal movement of said retainer, a nose formed upon said body, and means for normally retaining said nose in the compression-chamber.

19. In a baling-press, the combination with a framework provided with a compression-chamber and a plunger operating therein, the side walls of said compression-chamber being formed with longitudinal slots, of a retainer pivotally mounted within each of said slots, said retainer comprising a substantially straight body, provided at each end with oppositely-extending extensions, means

for limiting inward, pivotal movement of 35 said retainer, and means for exerting an outward pressure upon one end of said retainer.

20. In a baling-press, the combination with a framework provided with a compression-chamber and a plunger operating therein, 40 the side walls of said compression-chamber being formed with longitudinal slots, of a retainer positioned within each of said slots, said retainer comprising a body provided at one end with an extension and at its opposite 45 end with a head and a nose, the head constituting a stop, and means for exerting an outward pressure upon said extension.

21. In a baling-press, the combination with a framework, a compression-chamber 50 formed in said framework, a plunger operating in said compression-chamber, means for reciprocating said plunger, runners secured to said framework, of a transverse beam positioned upon said runners, near the front 55 ends thereof, a brake-pin pivotally mounted upon each of said runners near its front end, the rear end of each brake-pin extending beneath said transverse beam, and a rod connecting said pins, said beam constituting a 60 stop for limiting the pivotal downward movement of said pins.

In testimony whereof I affix my signature in presence of two witnesses.

JOHN J. STOPPLE.
